UNITED STATES PATENT OFFICE

JOHN CLARK HEIFNER, OF ASHLAND, OHIO

DESIGN FOR A HAT AND COAT RACK

Application filed January 9, 1932. Serial No. 42,437. Term of patent 3½ years.

To all whom it may concern:

Be it known that I, JOHN CLARK HEIFNER, a citizen of the United States of America, residing at Ashland, in the county of Ashland and State of Ohio, have invented a new, original, and ornamental Design for a Hat and Coat Rack, of which the following is a specification, reference being had to the accompanying drawings, forming part thereof, in which—

Figure 1 is an end elevational view of the article, showing my new design;

Fig. 2 is a front elevational view; and

Fig. 3 is a plan view.

I claim:

The ornamental design for a hat and coat rack as shown.

In testimony whereof I subscribe my signature hereto.

JOHN C. HEIFNER.
